UNITED STATES PATENT OFFICE.

HOWARD I. BECKER, OF SCHENECTADY, NEW YORK, ASSIGNOR TO GENERAL ELECTRIC COMPANY, A CORPORATION OF NEW YORK.

MEANS FOR PRODUCING ALTERNATING CURRENTS.

Application filed February 4, 1920. Serial No. 356,269.

My present invention relates to the production of alternating currents, and more particularly to the production of continuous high frequency alternating currents such as 5 are commonly employed for radio signaling.

One of the objects of my invention is to provide a simple and convenient apparatus for producing alternating currents from a direct current source. A more specific object 10 of my invention is to produce continuous high frequency currents suitable for radio signaling from a direct current source or a pulsating source of comparatively low frequency.

15 In carrying my invention into effect I employ an electron discharge device having an electron emitting cathode and an anode enclosed in an evacuated receptacle and preferably arranged in circular symmetry with respect to each other about an axis. The electrodes of this device are included in a circuit containing a source of current. The current flowing between the two electrodes may be controlled or varied in amplitude by 20 means of a magnetic field in the receptacle in a direction parallel to the axis of the electrodes or at right angles to the electrostatic field between the electrodes. If this magnetic field is varied between certain limits, 25 dependent in each case upon the structure of the device and the voltage applied to the electrodes, the current flowing between the electrodes may be varied between a maximum value which may be the value of the current 30 which would flow in the absence of any magnetic field and a minimum value which may be substantially zero. In practicing my invention it will probably be found desirable in most cases to provide a constant magnetic field of such a value that the current flowing 35 between the electrodes will be somewhat reduced from the amount which would flow in the absence of any magnetic field. The current flowing in the device may then be varied 40 between maximum and minimum values by means of a supplemental variable magnetic field which is produced by means of a current derived from the circuit between the two electrodes and which alternately assist and 45 oppose the constant magnetic field.

50 The novel features which I believe to be characteristic of my invention are set forth with particularity in the appended claims.

The invention itself, however, both as to its organization and method of operation will 55 best be understood by reference to the following description taken in connection with the accompanying drawing in which Figs. 1, 2, 3, 4 and 5 illustrate diagrammatically various circuit arrangements which may be 60 used in carrying my invention into effect, and Fig. 6 is a characteristic curve showing the relation between the current flowing between the electrodes at constant voltage and the strength of the magnetic field. 65

As indicated in the various figures of the drawing, an electron discharge device is employed comprising an evacuated receptacle 1, which is preferably of tubular form and which contains a filamentary cathode 2 and an anode 3 of cylindrical form, these two electrodes in the form of device here indicated being arranged in circular symmetry with respect to each other; that is, the active surfaces of the two electrodes are 70 substantially surfaces of revolution about a common axis which is preferably the major axis of the receptacle 1. While this arrangement of electrodes is desirable for securing the best results it is not essential, as satisfactory results may be obtained with arrangements of the electrodes which do not involve circular symmetry. A source of current 4 is connected to the two terminals 75 of the cathode 2 for heating it to incandescence to cause it to emit electrons for carrying current across the evacuated space between the two electrodes. An external circuit between electrodes 2 and 3 includes a source of current 5 for supplying current 80 for the operation of the device. In the present case, the source 5 is indicated as a direct current generator which is preferably shunted by condenser 6 for bypassing the high frequency components of the currents 85 set up in the circuit. This external circuit also contains an impedance device 7 which is preferably inductive. The constant magnetic field is provided by means of a coil 90 8 surrounding the receptacle 1, supplied with current from a direct current source 9, the strength of the magnetic field thus furnished being adjustable to a desired value 95 by means of variable resistance 10.

In the form of my invention indicated in 100 Fig. 1, an oscillatory circuit comprising an

inductance 11, which is wound around the receptacle 1 and variable capacities 12 and 13, is connected to the terminals of the impedance 7. The oscillatory circuit thus formed is tuned to the frequency of the oscillations which it is desired to produce.

The apparatus which I have indicated and described may be employed in various ways to produce oscillations, and various explanations may be advanced as to the manner in which the apparatus operates to produce oscillations. While I do not wish to limit myself to any particular theory or method of operation, the following description is given to indicate one way in which the manner of operation of the apparatus may be explained.

The relation between the magnetic field and current flowing in the plate or output circuit is indicated by the diagram of Fig. 6, the values of the magnetic field being plotted as abscissæ and corresponding current values as ordinates, the impressed voltage being constant. It will be observed that as the strength of the magnetic field is increased from zero the current remains substantially constant until the magnetic field has reached a value represented by *oa*. Further increase of field strength produces a rapid reduction of current until at a field strength *ob* the current has fallen to substantially zero.

In the operation of the device to produce oscillations, the constant magnetic field may be adjusted to a value somewhere between the values *oa* and *ob*. Under these conditions, when the circuits are completed current will start to flow in the plate circuit. This current will tend to come up to the maximum value possible with the particular field strength to which the constant magnetic field has been adjusted. In building up to this value a potential will be set up across the terminals of the impedance 7 which will cause the condensers of the oscillating circuit to become charged, and when the maximum current value has been reached these condensers will discharge through the coil 11 and produce a magnetic field therein which will add to the constant magnetic field, thereby producing a decrease in current in the plate circuit. The current in the oscillating circuit will then reverse in direction and oppose the constant magnetic field, thereby allowing the current in the plate circuit to increase. With each change in the current in the plate circuit a variation of potential will be produced across the terminals of the impedance 7, which will cause energy to be supplied to the oscillating circuit in such a way as to maintain oscillations therein. The oscillating current thus set up in this circuit may be withdrawn therefrom by means of a coupling transformer 15 the primary of which is included

in the oscillating circuit and the secondary of which supplies the alternating current produced to any desired utilization circuit.

The arrangement indicated in Fig. 2 operates in substantially the same manner as Fig. 1. It is evident that when potential changes are produced across the impedance 7 corresponding potential changes are produced across the electrodes of the device, and in this case the oscillating circuit is therefore connected directly across the electrodes of the device.

In Fig. 3 I have indicated an arrangement whereby the oscillating currents produced may be directly supplied to an antenna 16. In this case the antenna with its inductance and capacity forms the oscillating circuit and this circuit may conveniently be tuned to the variable inductance 17 as indicated. In case it is desired to employ the currents produced for radio telegraphy a key 18 may be inserted in the antenna for interrupting the production of high frequency oscillations to produce telegraphic signals.

The arrangement shown in Fig. 4 is equivalent to that shown in Fig. 1. In this case, however, the oscillating circuit instead of being directly connected to the terminals of the impedance 7 is inductively connected to this impedance by coupling the coil 19 to impedance 7, which in this case of course will be in the form of an inductance. This is a somewhat more flexible arrangement than that of Fig. 1 in that it permits a ready variation in the mount of energy supplied to the oscillating circuit by varying the coupling between coils 7 and 19.

The arrangement indicated in Fig. 5 is substantially the same as that shown in Fig. 4, only in this case the impedance 7 is in the form of a coil surrounding the receptacle 1, and the coil 19 is coupled to the coil 7 by also winding this coil around the receptacle 1. In this case I have indicated an antenna 20 as the utilization circuit to which the high frequency currents produced are supplied, and for purposes of radio telegraphy a key 18 may be inserted in the antenna, as in the arrangement of Fig. 3. With this arrangement the coil 7 is preferably wound around the receptacle in such a way that the field induced therein by the direct current component of the current in the plate circuit will assist the constant magnetic field. The oscillating current set up in the oscillatory circuit comprising coil 19, variable condenser 13 and primary of transformer 15, will alternately assist and oppose the combined magnetic fields produced by the other coils and thus cause the desired increase and decrease in the current in the plate circuit.

What I claim as new and desire to secure by Letters Patent of the United States is:

1. The combination in a system for produc-

- ing alternating currents of an electron discharge device comprising an evacuated receptacle containing an electron emitting cathode and an anode arranged in substantially circular symmetry and unobstructed spacial relation with respect to said cathode, means for producing a constant magnetic field in said receptacle in the space between said electrodes in a direction substantially at a right angle to the path of electrons between said electrodes, an external circuit between said cathode and anode containing a source of current, an oscillatory circuit connected in shunt relation to said external circuit and means for producing by means of the current flowing in said oscillatory circuit a magnetic field which is in the same direction as and which is superimposed upon the constant magnetic field.
2. The combination in a system for producing alternating currents of an electron discharge device comprising an evacuated receptacle containing an electron emitting cathode and an anode arranged in substantially circular symmetry and unobstructed spacial relation with respect to said cathode, means for producing a constant magnetic field in said receptacle in the space between said electrodes in a direction substantially at a right angle to the path of electrons between said electrodes, an external circuit between said cathode and anode containing a source of current, and a circuit containing inductance and capacity connected in shunt relation to said external circuit, a portion at least of the inductance of said circuit being in the form of a coil surrounding said receptacle and having its major axis substantially coincident with the major axis of said electrodes.
3. The combination in a system for producing alternating currents of an electron discharge device comprising an evacuated receptacle containing an electron emitting cathode and an anode arranged in substantially circular symmetry and unobstructed spacial relation with respect to said cathode, means for producing a constant magnetic field in said receptacle in the space between said electrodes in a direction substantially at a right angle to the path of electrons between said electrodes, an external circuit between said cathode and anode containing a source of current, an oscillatory circuit connected in shunt relation to said external circuit and means for producing by means of the current flowing in said oscillatory circuit a magnetic field which is superimposed upon the constant magnetic field and which alternately assists and opposes the constant magnetic field.
4. The combination in a system for producing alternating currents of an electron discharge device comprising an evacuated receptacle containing an electron emitting cathode and an anode arranged in substantially circular symmetry and unobstructed spacial relation with respect to said cathode, means for producing a constant magnetic field in said receptacle in the space between said electrodes in a direction substantially at a right angle to the path of electrons between said electrodes, an external circuit between said cathode and anode containing a source of current, an auxiliary circuit connected in shunt relation to said external circuit and means for producing by means of the current flowing in said auxiliary circuit a magnetic field which is in the same direction as and which is superimposed upon the constant magnetic field.
5. The combination in a system for producing alternating currents of an electron discharge device comprising an evacuated receptacle containing an electron-emitting cathode and an anode arranged in substantially circular symmetry and unobstructed spacial relation with respect to said cathode, means for producing a constant magnetic field in said receptacle in the space between said electrodes in a direction substantially at a right angle to the path of electrons between said electrodes, an external circuit between said cathode and anode containing a source of current, an auxiliary oscillating circuit coupled to said external circuit and supplied with energy therefrom, and means for producing by means of the current flowing in said oscillatory circuit a magnetic field which is in the same direction as and which is superimposed upon the constant magnetic field.
6. The combination in a system for producing alternating currents of an electron discharge device comprising an evacuated receptacle containing a cathode adapted to emit electrons independently of gas ionization, and an anode arranged in substantially circular symmetry and unobstructed spacial relation with respect to said cathode, an external circuit between said cathode and anode containing a source of current, an auxiliary oscillatory circuit coupled to said external circuit and supplied with energy therefrom, and means for producing by means of the current flowing in said oscillatory circuit a magnetic field in said receptacle in the space between said electrodes in a direction substantially at a right angle to the path of electrons between said electrodes.
7. The combination in a system for producing alternating currents of an electron discharge device comprising an evacuated receptacle containing a cathode adapted to emit electrons independently of gas ionization, and an anode arranged in substantially circular symmetry and unobstructed spacial relation with respect to said cathode, means for producing a constant magnetic field in the space between said electrodes in a direction substantially at a right angle to the path of electrons between said electrodes.

tion substantially at a right angle to the path of electrons between said electrodes, an external circuit between said cathode and anode containing a source of current, an auxiliary oscillatory circuit coupled to said external circuit and supplied with energy therefrom, and means for producing by the current

flowing in said oscillatory circuit a magnetic field in the space between said electrodes in the same direction as the constant 10 magnetic field.

In witness whereof, I have hereunto set my hand this 3rd day of February 1920.

HOWARD I. BECKER.
